UNITED STATES PATENT OFFICE.

BURTON D. MUNHALL, OF CLEVELAND, OHIO, ASSIGNOR TO THE UNION METAL MANUFACTURING COMPANY, OF CANTON, OHIO, A CORPORATION OF OHIO.

DESIGN FOR A STREET-LAMP.

40,737.

Specification for Design. Patented June 21, 1910.

Application filed April 12, 1910. Serial No. 555,114. Term of patent 7 years.

To all whom it may concern:

Be it known that I, BURTON D. MUNHALL, a citizen of the United States, residing at Cleveland, in the county of Cuyahoga and State of Ohio, have invented a new, original, and ornamental Design for a Street-Lamp, of which the following is a specification, reference being had to the accompanying drawing, forming part thereof.

The figure is a perspective view of a street lamp showing my new design.

I claim:

The ornamental design for street lamp as shown.

BURTON D. MUNHALL.
